UNITED STATES PATENT OFFICE.

JOSEPH L. ROUSSEAU, OF BROOKLYN, NEW YORK, ASSIGNOR TO MERTENTHALER LINOTYPE COMPANY, A CORPORATION OF NEW YORK.

MATRIX MANUFACTURE.

1,422,136.

Specification of Letters Patent.

Patented July 11, 1922.

Application filed August 1, 1921. Serial No. 488,865.

To all whom it may concern:

Be it known that I, JOSEPH L. ROUSSEAU, a citizen of the United States, residing at Brooklyn, in the county of Kings and State 5 of New York, have invented certain new and useful Improvements in Matrices Manufacture, of which the following is a specification, reference being had therein to the accompanying drawing.

10 My invention relates to matrices, such as are used in commercial linotype machines for the casting of type bars or slugs. These matrices, as heretofore made, have their character impressions located in the bottom 15 walls of so-called routing notches formed in the casting edges of the matrices, so that the ordinary slug, which is cast from such matrices, has its type characters mounted on pedestals rising above the quad line of 20 the slug, the pedestals of course being cast in the routing notches. In printing from slugs of the above description, it frequently 25 happens that the ink accumulates on the pedestals and finds its way onto the printed sheet, thus producing what is known as "smutting". This is particularly true of the larger or more open characters, which necessarily expose a considerable portion of 30 the pedestal surface both inside and outside of the type characters. My present invention is intended to obviate the foregoing objections, and to that end, I propose to manufacture the matrices in such manner 35 that the customary routing notches may be entirely eliminated. By thus doing away with the routing notches, the slugs may be cast without pedestals and the cause of 40 "smutting" thereby removed.

The precise manner in which the foregoing results are accomplished will be best understood from the detailed description to follow.

Referring to the drawings:

45 Figs. 1 to 4 show on an enlarged scale a matrix in different stages of manufacture;

Fig. 5 is a perspective view of the finished matrix;

50 Fig. 6 is an enlarged side elevation of a portion of a slug bearing type characters, some of which are cast from ordinary matrices, and others of which are cast from

matrices produced in accordance with my invention; and

Fig. 7 is a face view of the slug shown in Fig. 6.

55

The first step in my improvement consists in providing a suitable over-sized blank, such as that shown in Fig. 1. As will be observed, this blank A is formed on its character edge with a pad or raised portion 60 B which is intended to add enough excess metal to that edge of the blank to permit the subsequent operations hereinafter described. The pad B is shown as extending throughout the length of the blank edge, as 65 preferred, but it might suffice to have it located merely in the vicinity of character impression. The blank is produced in the regular way, namely, by stamping it out of a bar or sheet of raw material (brass), 70 and then, if desired or necessary, trimming it down to the desired size.

75 The second step consists in forming a very shallow notch C in the character edge of the blank, as by cutting or routing out a portion of the pad B, in the manner indicated in Fig. 2. In this figure, the final edge of the matrix is generally indicated by the dotted line D—D, and it is pointed out that the notch C stops short of this final 80 matrix edge. The purpose of cutting out the notch C is to remove or take off the tough outer skin of the blank edge and to expose a softer bed of metal for the punching of the character impression. By way 85 of explanation, it may be stated that the stamping out of the blank and the subsequent trimming operations have the effect of condensing or compacting the metal along its edges, thus rendering it difficult to drive 90 the punch directly into the edge of the blank with satisfactory results. This difficulty is herein overcome, as above indicated, by taking off the tough outer skin of the blank edge, which is permitted by producing the 95 blank in its original form with the pad of excess metal before mentioned.

100 The third step consists in punching the character impression E in the bottom wall of the notch C, which operation as just explained may be successfully performed by reason of the comparatively soft condition

of the metal exposed to the action of the punch. It will be noted that the character impression E is driven below the final edge of the matrix as indicated generally by the dotted line D—D, the depth of the strike being such that the face of the character impression will be located at the standard distance from the final matrix edge which in this country is .043".

10 The fourth and last step of my improvement consists in dressing down the edge of the blank to produce the final matrix edge, or more specifically, in milling down the pad B to the dotted line D—D. This is 15 done with the aid of suitable gage devices, which determine the exact amount of metal to be removed in arriving at the final matrix edge. The effect of such step is indicated in Fig. 4, and it will be seen that the notch C has been entirely eradicated in the 20 operation and that the character impression E now extends directly from the final matrix edge. As the notch C was cut to stop short of the final matrix edge, a small 25 amount of metal lying within the character zone is dressed down along with the rest of the excess metal on the blank edge during the milling operation. Of course, if the notch were cut down to the line of the final 30 matrix edge, as might be done, there would be no excess of metal at that point to be removed. However, the mode of procedure described is preferred, as any distortion of the metal during the punching operation is 35 thereby remedied in the milling process.

It will be understood that my improvement deals only with one phase of manufacture and that various other operations must be performed on the blank, in addition 40 to those above described, to bring it to its final form as shown in Fig. 5. These operations are well known to those skilled in the art and therefore require no mention.

The effect of my improvement is illustrated in Figs. 6 and 7, which show a slug 45 F bearing on its upper edge a line of type characters, those marked 1 being produced from the new matrices and those marked 2 being produced from the old matrices. As 50 will be observed, the characters 1 are cast directly on the edge of the slug body, whereas the characters 2 are cast on pedestals 3 rising from said edge. In printing from the characters 2, therefore, "smutting" may occur, 55 due to the presence of the pedestals 3, but no such objection may arise in the case of the characters 1, due to the absence of the offending pedestals. It is pointed out, however, that the type characters in either 60 case have their printing faces arranged at the same level or at the same distance from the quad line of the slug, so that matrices made in accordance with my improvement may be used freely with any of the old mat-

rices and also with the standard form of 65 mold employed in the commercial linotype machines.

While I have set forth the several steps which I propose to follow, these steps might be variously modified as to sequence or 70 otherwise without departing from the spirit of my invention. I therefore desire it to be understood that I do not limit myself to any specific mode of procedure except in so far as such limitations are specified in the 75 claims. It should also be understood that, although herein illustrated in connection with a matrix having a single character, the invention is equally applicable to matrices having two or more characters. 80

Having thus described my invention, what I claim is as follows:

1. In the art of manufacturing matrices, providing an oversized blank, forming in the edge of said blank a notch of a depth 85 not to extend below the final edge of the matrix, punching the character impression in the bottom wall of said notch and of a depth to extend below the final matrix edge, and thereafter dressing down the blank edge to 90 produce the final matrix edge.

2. In the art of manufacturing matrices, providing a blank with a pad of excess metal on its character edge, forming a notch in 95 said pad, punching the character impression in the bottom wall of said notch, and thereafter dressing down the pad of excess metal to eradicate said notch and to produce the final matrix edge.

3. In the art of manufacturing matrices, forming a notch in the character edge of a suitable blank, punching the character impression in the bottom wall of said notch, and thereafter dressing down the edge of the blank to eradicate said notch and to produce 105 the final edge of the matrix.

4. In the art of manufacturing matrices, stamping out of raw material a suitable oversized blank, routing out the edge of said blank so as to form a notch of a depth not 110 to extend below the final edge of the matrix, punching the character impression in the bottom wall of said notch and of a depth to extend below the final matrix edge, and thereafter milling down the blank edge to 115 produce the final matrix edge.

5. In the art of manufacturing matrices, providing a blank with a pad of excess metal on its character edge, punching the character impression through said pad of 120 excess metal and of a depth to extend below the final edge of the matrix, and thereafter dressing down the pad of excess metal to produce said final matrix edge.

In testimony whereof, I have affixed my 125 signature hereto.

JOSEPH L. ROUSSEAU.
